UNITED STATES PATENT OFFICE.

PETER SCHEPP AND JOHN FLACK, OF LA SALLE, ILLINOIS.

COLLAPSIBLE BARREL.

1,407,487.

Specification of Letters Patent. Patented Feb. 21, 1922.

Application filed January 12, 1921. Serial No. 436,661.

To all whom it may concern:

Be it known that we, PETER SCHEPP and JOHN FLACK, citizens of the United States of America, and residents of La Salle, 5 county of La Salle, and State of Illinois, have invented certain new and useful Improvements in Collapsible Barrels, of which the following is a specification.

This invention relates to containers such 10 as kegs and barrels, which are foldable to suitable proportions for convenient shipment in lots. The purpose of this invention is to provide a container of such character and one of proper rigidity and strength.

15 The object of the invention is accomplished by the device shown in the accompanying drawings, in which—

Fig. 1 shows the container in perspective as it would appear when folded or collapsed 20 to minimum dimensions.

Fig. 2 is an end view showing the device extended as it would appear when filled and ready for shipment.

Fig. 3 is a detail perspective illustrating 25 the attachment of the heads or ends of the container to the body portion.

Fig. 4 is a sectional view taken on the line 4—4 of Fig. 2.

With the end in view of providing a cylindrical container of the nature of and equal in strength to a barrel or keg of standard construction and which is foldable to compact condition, the design includes barrel staves or slats which are secured together 35 by flexible metallic bands or links, and heads which are hinged to the body portion and which are of cam or cleat form for expanding the body portion and closing its ends.

The body consists of staves 1 and 2, the 40 staves 1 being riveted to metallic bands 3 which are hinged to small metallic members 4 secured to the staves 2. The bands 3 are flexible to permit the barrel to assume a cylindrical form when the heads 5 thereof 45 are swung outwardly from the interior of the container to right angles with its axis. Each head 5 consists of two parts 6 and 7 which are centrally secured together by the pivot rivet 8. Each head is hinged to the

50 body of the container by a hinge 9 secured to staves 1 and to the part 7 of each head 5. The outer part 6 of the heads is provided with a pair of handles 10 by means of which it may be swung around its pivot 8 into engagement with cleats 11 on the stave mem-

bers 1 and 2 when it serves to expand the container from its rectangular folded condition to cylindrical form.

In preparing the device for shipment in lots the two parts of each head are swung 60 so that their longitudinal axes become parallel and the heads are then swung into the container around the hinges 9. This permits the device to assume the rectangular form shown in Fig. 1. To change the container 65 from the rectangular form to cylindrical into condition for receiving goods for shipment, one of the heads which then serves as the bottom of the container is swung to right angles to the axis of the container, thus 70 forcing the banded slats outwardly into substantially circular relation. The part 6 of the head is then swung around its pivot into the cleats 11, in which position it locks due to its pressure in expanding the body portion. The remaining head may be swung out 75 of the container to its side until the container is filled, when it too may be locked to its cleats 11 by the cam action of the member 6 thereof when swung around its pivotal 80 connection with the member 7.

We claim:

1. A container of the class described, comprising a plurality of staves arranged in cylindrical relation, flexible bands encircling 85 the staves and secured thereto, and heads for the container made in two parts pivoted together and one of which is of cam form for maintaining the container in cylindrical form by coacting with pressure against the 90 staves.

2. A collapsible container comprising a plurality of staves connected by flexible bands, and a head member comprising a pair of pivotally connected parts, one of said 95 parts being hinged to said container, the other of said part being rotatable relatively of said hinged part, the ends of said other part being formed to provide cams for coacting with the inner faces of said staves to 100 expand the container into cylindrical form by the rotation of said one part relative to said hinged part.

3. A collapsible container comprising a pair of oppositely disposed slats, a plurality 105 of intermediate slats secured together by flexible bands which are hinged to said opposite slats, and a head member comprising a pair of pivotally connected parts of substantially identical form, one of said parts being 110

hinged to one of said intermediate slats, the other of said parts being rotatable relatively of said hinged part so as to be shiftable into engagement with cleats formed on certain of 5 said slats, the ends of said other part being formed to provide cams for coacting with the inner faces of said slats to expand the

container into cylindrical form by the rotation of said one part relative to said hinged part.

Signed at La Salle, Ill., this 7th day of January, 1921.

PETER SCHEPP.
JOHN FLACK.
